BED-COVER CLAMP

Norman A. Hagedorn, Middletown, Ohio

Application June 17, 1947, Serial No. 755,121

2 Claims. (Cl. 5—320)

1

This invention relates to a clamp for bed-clothes and more particularly to a cover holder for a child's or infant's bed.

It is the object of the present invention to provide a cover holder for the sheets, blankets or other covering on an infant's or child's bed which will keep the cover securely in place following the tucking in of the child in bed, no matter how restless or active the child may be.

It is a further object of the invention to provide a cover clamp which is simple and economical in construction, which is readily manipulatable, and which presents no possibility of injury to the child by the attachment of the cover clamp to the bed.

It is also the purpose of the invention to provide an arrangement which may readily be attached to existing bed-frames at an insignificant cost, and which is pleasing in appearance when applied to either a new or old bed.

It is a further object of the invention to provide a cover holder in the form of a clamp which is conveniently and rapidly shifted between its operative and inoperative position, without possibility of injury to the attendant, the child or to the bedding, there being no possibility of tearing of the latter as is the case when spring clips and clasps are used.

The structure in accordance with the invention is characterized by such simplicity that the same requires no special skill in its manipulation or its application to the bed covers, there being no possibility of tearing the covers or doing any harm to the child or attendant as is likely in the handling of sharp clips attached to straps on the bed, which may become entangled, disarranged or shifted from their desired locations.

The invention proceeds upon the principle of providing a clamping bar on each side of a bed frame and extending longitudinally thereof, which is of substantial surface area, in order to exert the desired firm and safe clamping action without possibility of tearing of the bed covers. An arm extends from the clamping bar and is provided with one or more openings adjacent the free end thereof in sliding engagement with a guide rod which is attached to the inner side of the bed frame. The arm is provided with openings therein of slightly larger cross-sectional area than the guide rod so that the same may slide easily therealong. However, when the clamping bar is pressed into engagement with the covers on the bed, the resilient force of the bedding acting upwardly against the clamping bar serves to tilt or cant the clamping bar and

2

arm extending therefrom so that the arm enters into a binding engagement with the guide rod to maintain the clamp in tight frictional engagement therewith, which can only be released by the attendant when the clamping bar is pressed in a reverse direction, which may be supplemented by a lifting of the free end of the arm which is in binding engagement with the guide rod, thereby again permitting the free movement of the clamp along the guide rod. The tugging or pulling of the bed cover by the child in bed cannot release the clamp, for the force exerted thereby is in a direction to increase the gripping action of the arm against the guide rod. However, the release can be quickly and easily effected by the attendant in the manner described above.

Other objects and purposes will appear from the detailed description of the invention following hereinafter, taken in conjunction with the accompanying drawing, wherein

Fig. 1 is a plan view of a child's bed showing the application thereto of the cover holders in accordance with the present invention;

Fig. 2 is a vertical sectional view along line 2—2 of Fig. 1, showing in detail the mounting of the assembly on one side of the bed frame;

Fig. 3 is a plan view of the clamping bar and arm along line 3—3 of Fig. 2; and

Fig. 4 is a front elevation of a modified form of clamp assembly from that shown in Fig. 2.

As shown in Fig. 1, the cover holder 10 in accordance with the present invention is adapted to be placed on each side of the bed frame 1, a little more than a foot from the head of the bed, in order to clamp the bed covers 2 in place following the tucking in of a child or infant thereunder, so that the same cannot be disturbed by the tossing or other activity of the child. While two clamps as shown in Fig. 1 are adequate in most instances in order to clamp the cover adjacent the free edges thereof, it is readily understood that additional clamps may be provided at other points of the bed frame, and in those instances where it is desired to clamp bed-clothes at the foot 8 of the bed, such may be provided at that portion of the bed frame.

As shown in Fig. 2, a guide or slide rod 14, which is preferably of cylindrical form, is attached to the inner side of the bed frame formed of horizontal bars 3 and 4 with vertical slats 5 extending therebetween. The bar 14 may be readily mounted to the upper bar 3 and may slide in bracket 6 affixed to the lower bar 4 in order to fix its position as a guide or slide rod on the side

of the bed. The gooseneck extension at the upper end of rod 14 produces slight displacement thereof from the bed frame to permit a sliding of the clamping bar assembly therealong. The bottom 2' of the bed frame, formed of any suitable framework such as channel irons, springs, etc., is adapted to support a mattress 7 which is designed to be superposed by the bed covers 2 which are sought to be maintained in place in accordance with the present invention.

The clamp bar in accordance with the present invention is shown in Fig. 3 and may be formed of wood, metal or plastic material. It is preferably of rectangular configuration, running along the edge of the bed and terminating about an inch below the top of the bed cover. It has substantial surface area, of approximately 6 square inches, in order to exert a secure hold on the bed covers without causing a tearing thereof. This secure retention may be facilitated by the provision of corrugations on the bottom surface of the retaining clamp, or by providing a strip of rubber or other frictional material upon the bottom surface.

An arm 11, of resilient material such as metal or plastic, extends from the clamp bar 10 and is attached to the latter by screws, bolts, rivets, adhesive, welding, or by any other fastening means, and this arm preferably terminates in two branches 12 and 12' which have openings 13 and 13', respectively, of slightly larger cross-section than that of the guide or slide rod 14. If the arm 11 is of a cast metal or plastic, the arm 12' may be welded or fused to the arm 11 below arm 12. Apertures 13 and 13' permit a ready sliding of the clamp bar assembly along the guide rod 14. However, when the clamp bar 10 is pressed downwardly against the bed covers, the upward resilient force of the bedding acting on the bed clamp gives rise to a turning movement of the clamp 10 in a clockwise direction, as seen in Fig. 2, which produces a binding or clamping action of the arms 12 and 12' against the guide rod 14 in view of the close fit of the openings 13 and 13' along the guide rod; the left half (Fig. 2) of aperture 13 and the right half of aperture 13' bind against the respective lateral portions of guide rod 14. The tighter the clamp 10 is pressed against the bedding, the greater the degree of the resilient force exerted thereagainst and consequently the tighter is the frictional gripping action between the openings in arms 12, 12' and the guide rod 14. The same result is derived from a tugging of the covering 2 to pull the clamp bar 10 in a counterclockwise direction. Only when the attendant desires an intentional release of the clamp bar, can the secure engagement be released, which is effected by a tilting of the clamp bar 10 in a counterclockwise direction, which may be simultaneously coupled with a lifting of the bars 12 at the guide rod to release the frictional engagement at these points.

Fig. 4 shows an alternative arrangement for obtaining the spaced points of engagement between the clamping bar assembly and the guide rod 14. The resilient arm 21, when formed of sheet material, extends upwardly and outwardly from the clamp bar 20 and the horizontal portion 22 of the arm is bent reversely to provide a re-entrant portion 24 in parallel thereto, each of which portions are formed with openings, 26 and 26', of slightly larger dimensions than the guide

rod 14 in order to selectively slide therealong or come into gripping engagement therewith, depending upon the inclination of the clamp bar assembly with respect to the guide rod 14, as described below.

The lengths of the arms 11 and 21 in both of the illustrated embodiments of the invention are such as to extend onto the bed sufficiently to provide an effective clamping action by the clamp bars with which they are connected and to provide proper leverage for operation. While the most desirable features of the invention are attained by arrangements of the resilient arms as shown in the illustrated embodiments of the invention, it is possible to obtain some degree of clamping by the use of a single opening 13 in the spring arm.

While I have described my invention as embodied in a specific form and as operating in a specific manner for purpose of illustration, it should be understood that I do not limit my invention thereto, since various modifications will suggest themselves to those skilled in the art without departing from the spirit of my invention, the scope of which is set forth in the annexed claims.

I claim:

1. In combination with a bed-frame and bedding thereon, a cover clamp comprising a vertical guide rod mounted on the bed-frame, a clamp bar of substantial surface area adapted to be pressed into contact with the cover on the bedding, and an arm extending upwardly and laterally from said clamping bar and terminating in spaced arm portions having openings therein of slightly larger cross-sectional area than said guide rod, to permit sliding of the clamping bar and arm therealong but to remain fixed thereon near the lower limit of its travel, in frictional engagement with the guide rod, in consequence of the canting of the clamping bar and arm assembly by the upward resilient force exerted by the bedding, said spaced arm portions being formed by said arm and a reversely bent re-entrant terminal spaced therefrom.

2. In combination with a bed-frame and bedding thereon, a cover clamp comprising a vertical cylindrical guide rod mounted on the inside of the bed-frame, a clamping bar of substantial surface area adapted to be pressed into contact with the cover on the bedding and a resilient sheet metal arm extending from said clamp and terminating in a re-entrant portion spaced from another portion of said arm with aligned circular openings in each of said portions of said arm of slightly larger cross-sectional area than said guide rod to permit sliding of the clamping bar and arm therealong but to remain fixed thereon near the lower limit of its travel, in frictional engagement with the guide rod, in consequence of the canting of the clamping bar and resilient arm assembly by the upward resilient force exerted thereon by the bedding.
